United States Patent Office

Des. 188,303
Patented June 28, 1960

188,303

POCKET MIRROR OR SIMILAR ARTICLE

Maria Assunta Zoltowska, Paris, France, assignor to Murray Silverman, New York, N.Y.

Filed Sept. 1, 1959, Ser. No. 57,406

Term of patent 14 years

(Cl. D86—10)

Fig. 1

Fig. 2

Fig. 3

Fig. 1 is a front elevational view of a pocket mirror showing my new design;

Fig. 2 is a rear elevational view; and

Fig. 3 is a side elevational view thereof.

I claim:

The ornamented design for a pocket mirror or similar article, as shown.
